Primary Examiner—A. Hugo Word**Assistant Examiner—Eric Watterson****Attorney, Agent, or Firm—Ostrolenk, Faber, Gerb & Soffen****[57] CLAIM**

The ornamental design for a pressure clearing device for cleaning conduits, as shown and described.

DESCRIPTION

FIG. 1 is a left side elevational view of the pressure clearing device for cleaning conduits, showing my new design;

FIG. 2 is a rear elevational view thereof;

FIG. 3 is a right side elevational view thereof;

FIG. 4 is a perspective view thereof;

FIG. 5 is a right side elevational view corresponding to the side opposite shown that in FIG. 1;

FIG. 6 is a top view thereof; and,

FIG. 7 is a bottom view thereof.

FIG. 1

FIG. 2

FIG. 3

FIG. 4

FIG. 5

FIG. 6

FIG. 7
